US00D712836S

(12) **United States Design Patent**
Lee et al.

(10) **Patent No.:** US D712,836 S
(45) **Date of Patent:** ** Sep. 9, 2014

(54) **POWER SUPPLY PLUG**

(71) Applicant: **Samsung Electronics Co., Ltd.**,
Suwon-si (KR)

(72) Inventors: **Byong-Jeon Lee**, Seoul (KR);
Dong-Hyun Lim, Yongin-si (KR)

(73) Assignee: **Samsung Electronics Co., Ltd.** (KR)

(**) Term: **14 Years**

(21) Appl. No.: **29/454,343**

(22) Filed: **May 9, 2013**

(30) **Foreign Application Priority Data**

Nov. 12, 2012 (KR) 30-2012-0053879

(51) **LOC (10) Cl.** **13-03**

(52) **U.S. Cl.**

USPC **D13/133**

(58) **Field of Classification Search**

USPC D13/133, 146, 147, 154, 184, 199;

(57) **CLAIM**

The ornamental design for a power supply plug, as shown and described.

DESCRIPTION

FIG. 1 is a perspective view of a connector showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof, showing in use.

The broken lines in the drawings show unclaimed environment only and form no part of the claimed design.
